UNITED STATES PATENT OFFICE

ERNEST FLAGG, OF NEW YORK, N. Y.

LOCK AND LATCH MECHANISM

Application filed April 26, 1928. Serial No. 273,041.

This invention relates to a combined lock and latch mechanism which is particularly designed for doors, although not necessarily restricted to such use.

One of the principal objects of the present invention resides in the provision of a combined lock and latch mechanism which includes a common bolt serving in the capacity of a latch bolt and a lock bolt to preclude the necessity of employing a separate bolt for each purpose.

The invention furthermore comprehends a combined lock and latch mechanism which includes a common bolt having normally restrained means for projecting the same into a keeper when registered therewith, together with knob actuated means for retracting the bolt and key actuated means for rendering the knob actuated means effective and ineffective whereby the mechanism serves in the dual capacity of a latch and lock.

As a further feature, the invention comprehends in a lock and latch mechanism for doors, a knob controlled means for retracting the bolt, means controlled by a key insertable from the exterior for rendering the knob controlled means effective and ineffective, together with a permanent actuator for said latter means provided on the interior of the door which performs the function of a key used on the interior.

More specifically, the invention contemplates in a combined lock and latch mechanism for doors, a common bolt arranged in a housing carried by the door, which bolt is adapted to cooperate with a keeper on the door frame and which bolt is projected into the keeper when the door is closed by virtue of a normally restrained projecting means, a turnable knob being provided having operative connection with the bolt for retracting the same while a means controlled by an insertable and removable key is established for establishing or breaking the connection to render the knob respectively effective or ineffective.

The invention furthermore embodies in a combined lock and latch mechanism of the character set forth a key actuated tumbler assemblage which normally serves to render

the bolt retracting knob effective but which when manipulated by the key disposes the tumblers in such a manner as to render the bolt retracting knob ineffective.

As a still further object, the invention comprehends a tumbler assemblage including key engaging and actuating portions for separate cooperation with a regular key and with a master key, which master key may be employed in connection with a plurality of tumbler assemblages.

Other objects of the invention reside in the comparative simplicity of construction and mode of operation of the mechanism, the economy with which it may be produced and the general efficiency derived therefrom.

With the above recited and other objects in view, reference is had to the following description and accompanying drawings, in which there is exhibited one example or embodiment of the invention, while the claims define the actual scope of the same.

In the drawings:

Figure 1 is a longitudinal sectional view through the lock taken approximately on the line indicated at 1—1 in Figure 5 and illustrating the locking mechanism inactive and the bolt retracting knob operatively connected with the bolt.

Figure 2 is a similar view illustrating the mechanism with the bolt engaged in the keeper as a latch and subject to retraction by the knob.

Figure 3 is a similar view illustrating the position of parts as the same are being moved from the knob control to the locked condition.

Figure 4 is a similar view illustrating the position of parts showing the bolt engaging its keeper with the knob actuating mechanism ineffective and the bolt subject to retraction only after operation of the key mechanism.

Figure 5 is a vertical sectional view taken approximately on the line 5—5 of Figure 4 and on a slightly larger scale.

Figure 6 is a sectional view taken approximately on the line 6—6 of Figure 3.

Figure 7 is a detail sectional view taken approximately on the line 7—7 of Figure 5.

Figure 8 is a sectional view taken approximately on the line 8—8 of Figure 2.

Figure 9 is a perspective view of the keeper.

Figure 10 is a perspective view of the bolt 5 projecting arm.

Figure 11 is a perspective view of the bolt.

Figure 12 is a perspective view of the rack-bar shifting arm.

Referring to the drawings by characters 10 of reference, A represents a door frame and B the door. The combined lock and latch mechanism includes a housing 15 which is preferably arranged in a mortise in the door stile in the usual manner. A common bolt 16 is mounted within the housing for projection through the bolt opening 17 of the face plate 18 of the housing, from its normally retracted position within the housing. The bolt 16 is recessed at 19 to receive the forward end of a bolt retracting rack bar 20, which forward end is provided with a knuckle 21 receiving a transverse pin 22 extending through the bolt and pivotally connecting the rack bar 20 with the bolt. A bolt projecting means is also housed by the housing 15 and the same consists of an arm 23 which is secured to a shaft 24 for turning movement therewith. The free end of the arm is bifurcated and the furcations 25 straddle the forward portion of the bolt retracting rack bar 20 and engage the knuckle portion 21 thereof. The arm 23 is normally swung in a position to project the bolt 16 from the housing by a flat spiral spring 26, one terminal of which is anchored to a collar 27 on the shaft 24 while the opposite terminal 28 is hooked around an anchoring point. The tendency of the convolutions of the spring 26 to unwind causes the shaft 24 to turn in a clockwise direction and hence swings the arm to the left in Fig. 1, thereby projecting the bolt 16 through the bolt opening 17.

45 In order to provide means for normally restraining the bolt against projection and for releasing the same when the door is closed and in registry with the bolt keeper, a depending lug 29 is formed on the bolt adjacent its rear end and said lug is engaged behind an upwardly projecting detent 30 on a detent lever 31 which is fulcrumed for lateral swinging movement on a pivot 32 which projects upwardly from the bottom wall 33 of the housing. The detent lever is normally swung laterally to dispose the detent 30 in front of the bolt lug 29 by a coiled expansion spring 34 which engages between the rear notched terminal of the detent lever 60 and the side wall 35 of the housing. A transverse guide pin 36 extends through the notched rear terminal of the detent lever and the spring 34 surrounds said pin. The forward arm 37 of the detent lever impinges 65 against a plunger 38 which is mounted for

lateral movement in an opening 39 in the side wall 35 of the housing 15 and said plunger is provided with a head 40. A keeper 41 having a bolt receiving socket 42 is mounted on the door frame in the usual manner and is 70 provided with an extension 43 disposed at a right angle thereto. The extension is provided with an outwardly projecting finger 44 which is adapted to be engaged by the plunger head 40 when the door is moved to the closed 75 position. This effects a relative movement of the plunger 38 within the plunger opening 39 and results in effecting through its engagement with the detent lever arm 37 a lateral swinging movement of the detent lever to 80 throw the detent 30 from engagement with the bolt lug 29 so that the spring 26 functions to project the bolt 16 into the keeper. It is obvious that from this arrangement the bolt 16 is always retracted within the housing and within the confines of the door edge except when the door is in closed relation to its frame. Obviously, this prevents the catching and tearing of the clothing on the bolt or damage to the person which might 85 otherwise be caused if the bolt is in a projected position when the door is open.

The mechanism includes a bolt retracting means which consists of a spindle 45 extending transversely through the door and 90 through the housing 15, said spindle being provided with knobs 46 attached to its opposite ends. A pinion 47 is carried by the spindle for turning movement therewith and its teeth 48 are normally designed to engage 100 with the rack teeth 49 on the rack bar 20. It thus follows that when the door has been closed and the bolt 16 projected into the socket 42 of the keeper 41, it is only necessary to manipulate either of the knobs to turn the pinion 47 in a clockwise direction for 105 retracting the bolt to open the door. When the bolt has been retracted through the medium of the knobs, the initial movement of the door to an open position will relieve the pressure of the finger 44 on the plunger 38, thereby allowing the spring 34 to function to swing the detent lever 31 to a position to dispose the detent 30 in front of the bolt lug 29. This, obviously, will hold the bolt retracted 110 against projection by the spring 26 until such time as the door is again closed.

In order to provide means for rendering the knob retracting means ineffective or inoperative so that the door when closed will 115 be locked against retraction by manipulation of the knobs, a suitable key controlled tumbler organism is employed for use in connection with a device for moving the teeth of the rack bar 20 out of engagement with the pinion 47. The device for shifting the rack bar consists of an arm 50 which is fulcrumed for swinging movement on a transverse pin 51 and which is engaged by and connected at its free end 52 with the hooked terminal 120 125 130

of the spring 26. The arm 50 is provided with depending laterally spaced knuckles 53 carrying a transverse pin 54 which also extends through a longitudinal slot 55 in the rack bar 20. The arm 50 is further provided with an upstanding flange 56 at one edge thereof, the purpose of which will be hereafter set forth. The arm is also provided with a transversely disposed T-shaped rib 57.

The tumbler assemblage includes a plurality of tumbler plates 58 arranged in side by side relation within the upper portion of the housing 15 for relative longitudinal sliding movement on transverse supporting pins 59 which extend through slots 60 provided in the tumbler plates. The lower ends of the tumbler plates are formed with T-shaped notches 61, the restricted portions 62 of which correspond in length approximately to the width of the T-shaped rib 57 and which restricted portions extend completely through the lower edge of the tumbler plates. The tumbler plates are further provided with keyhole slots 63 and 64 which are adapted to be adjusted by their respective keys to an aligned position which simultaneously disposes the T-shaped notches 61 in alignment, it being understood that the notches 61 and the keyhole slots are normally disposed out of alignment under the action of a tumbler spring 65 which engages with the rear edges 66 of the tumbler plates. It is, therefore, obvious that the rear edges 66 are disposed in alignment when the T-shaped notches 61 and the keyhole slots 63 and 64 are staggered or out of alignment. The keyhole slots 63 are adapted to receive a regular key 67 which is provided with suitable notches 68 in its shank to correspond with the arrangement of the keyhole slots 63 so that when the key is inserted and turned in the proper direction, the T-shaped notches will be aligned and moved as illustrated in Figures 3 and 4 to a position which will admit the T-shaped rib 57 through the restricted portions 62 of the T-shaped notches 61, it being understood that the spring 26 will effect the upward swinging movement of the arm 50. Obviously, this moves the rack bar 20 to a position where its teeth 49 are out of engagement with the teeth 48 of the pinion 47. When this occurs, it is apparent that when the door is closed and the bolt 16 shot home into the opening 42 of the keeper, the knob spindle is ineffective for the purpose of retracting the bolt and it is necessary to insert the key through a suitable key barrel 69 having a keyhole slot 70 for the purpose of again arranging the tumblers and actuating arm 50 to swing the arm 50 downwardly to cause a re-engagement of the rack teeth with the pinion. The means for swinging the arm downwardly by use of the key 67 consists of a collar 71 mounted for rotation in a bearing opening 72 in the wall 35 of the housing, the bearing being

provided on its inner side with a recess 73 corresponding to the size and shape of the inner terminal of the key shank. A similar collar 74 is mounted in axial alignment with the master keyhole notches 64 and the collars 71 and 74 are provided with interengaging gear teeth 75 and 76 so that turning movement of the collar 71 is transmitted to the collar 74. The collar 74 is provided with a radial cam finger 77 which is designed to engage with the upper edge of the flange 56 of the arm 50 to cam or move the arm downwardly. It is, of course, to be understood that after the T-shaped slots 61 have been aligned and moved to a position to receive the T-shaped rib 57, that when the key is removed the spring 65 functions to again stagger the tumbler plates so that the rib 57 is locked and retained in place to additionally secure the mechanism in its locked condition. It should also be understood that the movement of the key in unlocking the door allows the spring 65 to disalign or stagger the notches 61 before removal of the key so as to prevent the rib 57 from re-entering the notches and to thus maintain the unlocked condition of the bolt. In order to prevent possible forcing of the bolt inwardly by a jimmy or other tool, it will be observed that the rack bar 20 when moved upwardly to the position illustrated in Figure 4 has its rear terminal disposed in alignment with and in close proximity to a rib 78 which projects inwardly from the rear wall 79 of the housing 15. It is, of course, understood that the master key and the master keyhole slots 64 perform identically the same function as the regular key 67 except that the tumbler plate actuating notches will be differently arranged from the regular key while they will be common to a plurality of locks of the same general character.

In order to provide a permanent means operable from the interior of the door to function in the same capacity as the keys, an actuator element 80 is operatively connected with the collar 71 for the purpose of turning the collars 71 and 74. The actuator element 80 has connected therewith a manipulating button 81 which projects inwardly of the door and which serves as the means for turning the element. The actuator element has keyed thereto by a key 82 a sleeve 83, which sleeve is provided adjacent one of its ends with gear teeth 84. A second sleeve 85 is carried by a stub shaft 86 for turning movement therewith and said latter sleeve is provided with gear teeth 87 designed to mesh with the gear teeth 84. A spring strip 88 has one terminal 89 anchored to the sleeve 83 and is spirally coiled and loosely wound around the sleeve, as illustrated in Figure 7. The other end is reversely coiled and partly trained around the sleeve 85 with its terminal 90 anchored thereto. The stub shaft 86 is

connected with an axially aligned stub shaft 91 which lies within the housing 15 and which has mounted thereon for turning movement therewith a tumbler plate shifting element 92. The tumbler plates are provided with upwardly projecting lugs 93 co-related with each other in the same manner as the keyhole openings 63 and 64 so that turning of the shifting element 92 in a counterclockwise direction, as illustrated in Figure 1, will cause the ear 94 of the shifting element to engage with the lugs 93 to shift the T-shaped notches 61 into alignment with each other and into registry with the T-shaped rib 57, the element being further provided with a stop ear 95 which engages with the upper edges of the tumbler plates to limit its turning movement in counterclockwise direction. In operation, when the button 81 is manipulated with the parts shown in the position in Figure 1, the actuator element 80 will be turned in the clockwise direction indicated by the arrow in Figure 7. This will through the engagement of the gear teeth 84 and 87 effect a counterclockwise turning movement of the sleeve 85, as indicated by the arrow in Figure 7, thereby turning the stub shafts 86 and 91 to turn the tumbler plate shifting element in a counterclockwise direction, as viewed in Figure 1, causing the ear 94 to engage with the tumbler lugs 93 to shift the tumbler plates to the right in Figure 1 for disposing the T-shaped notches 61 in alignment with each other and in registry with the T-shaped rib 57 so that the spring 26 will function to swing the arm 50 upwardly for disengaging the teeth of the rack 20 from the teeth of the pinion 47. From this, it is apparent that the closing of the door and release of the bolt by the detent means will permit locking of the door so that the same can only be opened from the exterior by use of the regular key or master key. It is apparent that when the button 81 is released the spring strip 88 will function to return the same to its normal position, permitting the spring 65 to again urge or shift the tumbler plates so as to dispose the T-shaped notches out of alignment. When it is desired to unlock the door from the interior, the button 81 is again manipulated to turn the sleeve 83 in its clockwise direction so that the meshing of the gear teeth 84 and 87 initially effects the turning of the sleeve 85, the stub shafts 86 and 91 and the shifting element 92 in a counterclockwise direction to cause the ear 94 to engage with the tumbler plate lugs 93 and shift the tumblers to a position where the T-shaped notches 61 are in alignment with each other and in registry with the rib 57. Continued manipulation of the button 81 in the same direction will allow, due to the disengagement of the teeth 84 and 87, a further turning movement of the sleeve 83 which will cause the collars 71 and 74 to be turned

to bring the finger 77 into engagement with the flange 56 to throw the arm 50 downwardly and again effect the re-engagement of the teeth 49 of the rack 20 with the teeth 48 of the pinion 45 so that upon manipulation of the inner knob the bolt will be retracted. When the button 81 is released, the portion or convolutions of the spring 88 which are now under tension will set up a retrograde movement on the sleeve 83 and will cause the parts to be returned to their normal position. During the counterclockwise turning movement of the sleeve 83, the gear teeth 84 will be again re-engaged with the gear teeth 87 so as to turn the shifting element 92 in a clockwise direction to permit of the spring 65 functioning to again stagger the notches 61 so that the lower edges of the tumbler plates engage over and prevent the spring 26 from moving the arm 50 upwardly. When one of the keys is inserted from the exterior with the mechanism in locked condition, it is obvious that the shifting element 92 works in conjunction and simultaneously with the key actuated means and its mechanism.

What is claimed is:

1. In a locking and latching mechanism for doors and the like, a common bolt carried by the door and normally projectable into a keeper on the door frame, a turnable actuating knob, interengageable means carried by the knob and bolt for establishing a connection therebetween to effect the retraction of the latter by turning of the knob when said means are engaged and a key controlled mechanism for effecting the engagement and disengagement of said means to render the knob respectively effective and ineffective, said key controlled mechanism including a plurality of shiftable tumbler plates having normally disaligned notches in one edge adapted to be aligned by a key, a member for normally effecting the disengagement of the knob and bolt connecting means, said member having a rib adapted to enter the notched edges of the tumbler plates when aligned by the key and means turnable by and with the key for engaging and moving said member to a position to re-engage the knob and bolt connecting means.

2. In a combined latch and lock mechanism, a common lock and latch bolt, a knob, means for connecting the knob with the bolt for retraction by the knob, a common means for projecting the bolt and disengaging the knob and bolt connecting means and key actuated means for respectively engaging the knob and bolt connecting means, retaining the same in connected relation or permitting the same to be disengaged.

3. In a combined latch and lock mechanism for doors or the like, a common lock and latch bolt, a turnable knob, means carried by the bolt and means carried by the knob

for connecting the same to effect the retraction of the bolt upon turning of the knob, a common means for projecting the bolt and disengaging the knob and bolt connecting means and a key actuated means respectively 5 operable to engage the bolt and knob connecting means, to allow for their disengagement or to retain them engaged.

Signed at New York, in the county of New
10 York and State of New York, this 23rd day
of April, A. D. 1928.
